(57) CLAIM

The ornamental design for a front face of a plaque, as shown and described.

DESCRIPTION

FIG. 1 is a front elevational view of a front face of a plaque showing my new design; and,

FIG. 2 is a front elevational view of a front face of a plaque of a second embodiment showing my new design.

The broken lines form no part of the claimed design.

1 Claim, 2 Drawing Sheets
